HANDLE

Montgomery Ferar, Huntington Woods, Mich., assignor to Whirlpool Corporation, a corporation of Delaware

Application January 31, 1958, Serial No. 49,462

Term of patent 14 years

(Cl. D10—8)

The characteristic features of my invention reside in the full line portions of the drawings.

I claim:

The ornamental design for a handle, as shown.
